Specification of Letters Patent.

Patented May 28, 1912.

Application filed July 6, 1911. Serial No. 637,124.

To all whom it may concern:

Be it known that I, ALBERT PARADIS, a citizen of the United States, residing in the city and county of Philadelphia, State of Pennsylvania, have invented a new and useful Box, of which the following is a specification.

My invention consists of a paper or other box in which provision is made for the contents of the box in good and marketable condition, the essential feature of the invention comprising a plate or ledge of novel construction on which said contents are rested, and a plurality of supports for said ledge, said supports being composed of a cord which is doubled on itself and formed into an endless loop lengths of which pass under said ledge and then through the sides of the body of the box, the opposite terminals of 20 the loop outside of the body then being tightened over the lid of the box, and the cord knotted, the knot being located under a tongue on said lid so as to be lowered below the upper surface of the lid avoiding 25 a bulge on said surface, said tongue being controlled and covered with said knot by a seal, all serving to prove the intact condition of the box at its place of reception or delivery, while the lid is firmly held in position 30 on the body of the box and prevented from improper opening. When the box is opened, the loop remains a fixture of the same and so is adapted to be reused, the knot and said tongue not having been injured 35 or destroyed by said seal, so that another knot may be formed on the length H and a fresh seal applied and secured to the portion of the box outside the opening formed by said tongue while again freely 40 covering the latter and the knot beneath the same without applying the adhesive material of the seal to the knot.

The invention is satisfactorily illustrated in the accompanying drawing, but the important instrumentalities thereof may be varied, and so it is to be understood that the invention is not limited to the specific arrangement and organization shown and described.

Figure 1 represents a perspective view of a box embodying my invention. Fig. 2 represents a horizontal longitudinal section on line $x-x$ Fig. 3. Fig. 3 represents a transverse vertical section on line $y-y$ Fig. 2. Fig. 4 represents a perspective view of the

cord employed. Figs. 5 and 6 represent perspective views of portions of the lid of the box showing the tongue employed in different positions. Fig. 7 represents a perspective view of the ledge employed.

Similar letters of reference indicate corresponding parts in the figures.

Referring to the drawings:—A designates the body of a paper box, and B designates the lid thereof, said parts excepting the features of my invention applied thereto being of ordinary construction. Within the body, is the plate or ledge C on which the goods or contents of the box are rested, said ledge being preferably card or paste board or other pliable but sufficiently strong material. Under said ledge are placed two lengths D. D. of an endless loop of cord, the same passing upwardly from the sides thereof and then out of the body A through the openings E. E., converging over the sides and top of the lid forming the loops J, K which are on opposite sides of the lid. The two lengths of cord in primary condition form the loop G, its ends being united by the knot F, as shown in Fig. 4. The converged end of the loop J is united by said knot F, shown also in Fig. 1, and has a length H of cord continuous of the loop, the same extending transversely across the top of the lid and is passed through the opposite converged end of the loop K and twined back therefrom on itself forming the supplemental loop L which is drawn up and tightened and so tightens said loops and cord within the body. The loop L is secured by the knot M thus holding the piece of cord tightly on the box while the ledge C is held up in a plurality of places and so prevented from bulging downwardly and thereby keeps the goods imposed thereon firm against the inner side of the lid of the box and prevents shifting and mousing of the same.

In order to prevent the knot M from bulging upwardly and forming an irregular surface on the top of the lid, I form on said top the hinged tongue N, which is punched out from the material of said top and adapted to be raised, as in Fig. 6. Then the knot M and an adjacent portion of the piece of cord is passed under said tongue and the latter closed down when the knot is depressed and occupies a position below the tongue and the latter occupies the opening from which said tongue is cut or punched out. In order

to prevent rising of said tongue, I apply thereover the seal P which is secured by adhesive material to the portion of the top of the lid, around said tongue, thus covering 5 said tongue and rendering it comparatively immovable in upward or outward direction.

When the seal is broken the knot M is accessible and the same may be opened, thus loosening the piece of cord, and separating 10 the loops J. K. and length H thereof, when the lid may be raised and the contents of the box are accessible the same being found in admirable and marketable condition in which they were originally packed.

15 When the cord is applied primarily to the box and passed through the openings E, and the knot F is formed, the resultant loops J. K. prevent the cord from being drawn out or removed improperly from the box in 20 either direction and so under ordinary circumstances, the cord remains a fixture of the box ready for subsequent re-use.

The tray C is formed of a piece of material having its side end portions upturned 25 and downturned producing the grooves or inverted V-shaped sides Q, the top bands of which are reinforced by pieces R of suitable fibrous material secured thereon.

30 The walls of the grooves or inverted V-shaped sides Q are pliable or flexible and so are adapted to be fitted on the top edges of the body of the box whereby the ledge is

suspended in position and admits of the lid being placed over said walls, thus retaining the latter in position on the body while the 35 ledge proper acts as a transverse brace to prevent collapsing of the body of the box, then the two lengths D of the cord serve to balance the tray and cause uniform upward pressure thereon from below preventing distortion of the tray when said cord is tightened, and thus the tray will be held flat 40 against the underside of the contents of the box.

Having thus described my invention what 45 I claim as new and desire to secure by Letters Patent, is:-

In a box, a plurality of openings in the sides thereof, and a pliable tongue integral with the lid thereof, and an endless loop of 50 cord partly in the box, passed partly through said openings and partly outside of the box, the outside portions converging toward each other, said portions being adapted to be drawn together and connected 55 by a knot, the latter being adapted to be passed under said tongue and covered by the same, leaving the tongue flush with the adjacent portions of the lid.

ALBERT PARADIS.
